UNITED STATES PATENT OFFICE.

ROBERT H. IRONS, WILLIAM BROWN, AND JOHN W. SHEPERDSON, OF HARRISBURG, PENNSYLVANIA.

METAL-POURING APPARATUS.

1,152,319.

Specification of Letters Patent. Patented Aug. 31, 1915.

Application filed June 28, 1915. Serial No. 36,854.

To all whom it may concern:

Be it known that we, ROBERT H. IRONS, WILLIAM BROWN, citizens of the United States, and JOHN W. SHEPERDSON, a subject 5 of the King of Great Britain, residing at Harrisburg, in the county of Dauphin and State of Pennsylvania, have invented certain new and useful Improvements in Metal-Pouring Apparatus; and we do hereby 10 declare the following to be a full, clear, and exact description of the invention, such as will enable others skilled in the art to which it appertains to make and use the same.

This invention relates to metal pouring 15 and casting apparatuses, and has for an object to provide a pouring system embodying a sprue plate carrying a central pouring fountain with ducts radiating from the fountain, and with a plurality of laterals 20 leading from the radial ducts and communicating with the outlets, such outlets being in communication with the pouring fountain through uniform runs of ducts and ducts offering equal resistance to the flow 25 of the molten metal between the fountain and the independent and individual outlets.

A further object of the invention is to 30 provide a sprue plate having a central pouring fountain and a plurality of outlets spaced about the sprue plate communicating with the fountain by ducts, the resistance from the fountain to each outlet being the equivalent of the resistance to each other 35 outlet in the sprue plate, and each of said outlets covered by a mold in substantially the usual and ordinary manner.

With these and other objects in view the 40 invention consists in certain novel features of construction, combination and arrangement of parts as will be hereinafter more fully described and claimed.

In the drawings: Figure 1 is a view of the sprue plate showing in one quarter the 45 furrows for the receipt of the conduit bricks, in another quarter the conduit bricks in plan, in the third quarter the conduit bricks in horizontal section, and in the fourth quarter the structure complete with the 50 mold set over the outlets. Fig. 2 is a view in side elevation of the structure showing the same number of molds in position as shown at Fig. 1. Fig. 3 is a plan view of a sprue plate having conduits arranged differently 55 than at Fig. 1. Fig. 4 is a plan view of a

sprue plate showing a still different arrangement of the conduits.

Like characters of reference designate corresponding parts throughout the several views.

The improved metal pouring apparatus which forms the subject-matter of this application embodies a sprue plate of any usual and ordinary form shown at Figs. 1 and 4 as circular, and at Fig. 3 as rectangular, it being understood, of course, that the particular form or general shape of the sprue plate is not essential to the present invention.

At some substantially central point in 70 the sprue plate 10 or 10' a pouring opening 11 or 11' is produced above which and resting upon the sprue plate a pouring fountain 12 is erected. Leading from the pouring opening 11 or 11' in symmetrical order, as for instance, radially as shown at Figs. 1 and 4 and in alinement as shown at Fig. 3, are furrows in which are located the conduit bricks. The furrows in the sprue plates themselves are indicated at 13, and are similar in each sprue plate irrespective of the shape and conform to the transverse sectional area of the conduit bricks 14. At certain positions in the run of the conduits T-bricks 15 are employed to connect the several conduits with the laterals leading therefrom.

At the extremities of the terminal laterals sprue bricks 16 are employed having outlets 17 therein. Over the outlets 17 molds 18 are erected as indicated at Figs. 1 and 2, each of said molds covering and embracing a single outlet.

From an examination of Figs. 1, 3 and 4, which illustrate three embodiments of the 95 present invention, it will be obvious that each outlet is at a distance from the fountain exactly equal to each other outlet measured through the conduits, and that the resistance of the conduits leading to each outlet is exactly the same as the resistance leading to each other outlet from the fact that equal number of laterals are in each case taken off from the main conduit and that the terminal laterals are in each case grouped about their feeders to offer identical resistance.

It is well known, of course, that in the casting of ingots from either the open-hearth or the Bessemer processes two forms 110

of pouring are employed, ordinarily referred to as "top pouring" and "bottom pouring." It is also known that for quality and uniformity of the resulting ingot, the bottom pouring process is preferred, but that it has been found difficult and heretofore impossible to so group a large number of molds about a central fountain as to make the uniform distribution of the metal possible, and 5 to offer equal facility for each mold to fill from the metal-conveying conduit. Where a plurality of molds are located upon a single conduit it is well known that some molds will fill more readily than other molds, and 10 that the metal will at times suddenly flow out of a mold that has taken steel rapidly into a mold that has lagged behind in the filling, producing what is known in the art as "surging" which is detrimental to the 15 quality of the ingot. By the location of each mold over an outlet in a terminal conduit brick no opportunity is afforded for surging, while all of the molds will fill slowly and uniformly from the bottom which produces an ingot of the highest possible 20 quality.

It should be noted that the present apparatus differs from all known apparatuses employing radial ducts in that provision is 25 made to locate each mold over an outlet in a terminal brick and that each of such outlets is equally distant from the fountain, measured by way of the conduits, with equal resistance interposed between the fountain and each outlet.

What is claimed is:—

1. A metal pouring apparatus comprising a sprue plate having a pouring fountain, and conduits leading therefrom; of a plurality of several conduit units each communicating with a conduit and provided with an outlet, each of said outlets being equally distant from the fountain measured through the conduits.

45 2. A metal pouring apparatus comprising a sprue plate having a pouring fountain erected thereon, and conduits leading therefrom; of laterals leading from such conduits, and terminal conduit sections in 50 communication with such laterals, each of

said terminal sections being provided with an outlet being so located as to present equal conduit resistance to the flow of metal from the pouring fountain.

3. In a metal pouring apparatus, a base 55 having a pouring opening, and conduits leading therefrom; lateral conduits communicating with the first-mentioned conduits; and terminal conduits communicating with the lateral conduits, each of said terminal conduits being provided with an outlet, the outlets being so positioned as to be equally distant from the pouring opening measured through the conduits and to offer equal conduit resistance to the flow of metal. 60

4. In a metal pouring apparatus, a bed provided with a pouring opening; a plurality of conduits leading from the opening of equal length; a plurality of lateral conduits communicating with the first-mentioned conduits, all being of equal length; and a plurality of terminal conduits communicating with the lateral conduits and provided with outlets, so that to reach each outlet the metal must travel the same distance and make the same number of turns in each case. 70

5. In a metal pouring apparatus, a bed provided with a pouring opening; a plurality of conduits of equal length and capacity leading from said pouring opening; a plurality of lateral conduits of equal length and capacity leading from the termination of the first-mentioned conduits; and a plurality of terminal conduits extending from 80 the extremities of said lateral conduits and each provided with an outlet, the outlets being equally distant from the pouring opening measured through the conduits and the 85 lengths and capacities of like parts of the 90 conduits offering like resistances to the flow of metal by reason of the symmetrical disposition of all the metal passages around the pouring opening.

In testimony whereof we affix our signatures.

ROBERT H. IRONS.
WILLIAM BROWN.
JOHN W. SHEPERDSON.
